ATTORNEY

UNITED STATES PATENT OFFICE.

FRED HOYT, OF SEATTLE, WASHINGTON, ASSIGNOR TO UNIVERSAL HIGH POWER
TELEPHONE CO., OF KING COUNTY, WASHINGTON.

DESIGN FOR A COMBINED JARDINIÈRE AND GRAFANOLA STAND.

50,419.

Specification for Design.

Patented Mar. 6, 1917.

Application filed September 13, 1916. Serial No. 119,984. Term of patent 7 years.

To all whom it may concern:

Be it known that I, FRED HOYT, a citizen of the United States, and a resident of Seattle, in the county of King and State of Washington, have invented a new, original, and ornamental Design for a Combined Jardinière and Grafanola Stand, of which the following is a specification, reference being had to the accompanying drawing, forming a part thereof.

The figure is an elevation of a combined jardinière and Grafanola stand illustrating my new design.

I claim:

The design for a combined jardinière and Grafanola stand as shown.

FRED HOYT.
